C. SHARPS.

Primer for Fire-Arms.

No. 9,820.

Patented June 28, 1853.

UNITED STATES PATENT OFFICE.

CHRISTIAN SHARPS, OF HARTFORD, CONNECTICUT.

IMPROVEMENT IN PERCUSSION-PELLETS

Specification forming part of Letters Patent No. 9,820, dated June 28, 1853.

To all whom it may concern:

Be it known that I, CHRISTIAN SHARPS, of Hartford, in the county of Hartford and State of Connecticut, have invented a new and useful Improvement in Percussion Caps or Pellets, of which the following is a full, clear, and exact description, reference being had to the accompanying drawings, which form part of this specification, and in which—

Figure 1 is a longitudinal section of the pellet magazine or chamber of a self-priming musket with pellets therein, and a view in perspective of a pellet-charger, partly loaded, for filling the magazine. Fig. 2 is a longitudinal section of the charger. Fig. 2 is a view in perspective of the two parts of a pellet-case, which, when fitted together and loaded with detonating material, form the pellet. Fig. 4 is a transverse section of a pellet in process of manufacture; and Fig. 5 is a similar view of the finished cap or pellet, the drawings being on an enlarged scale for the better exhibition of the parts.

The ordinary open percussion cap or pellet is subject to many objections. It is bulky to carry and inconvenient to use, requiring the hand to insert it on the nipple of the gun, and is liable to shed its detonating powder. Numerous other objections, which it is not necessary to specify, exist, and it has long been a desideratum to produce a closed cap or pellet easily made and suitable for self-priming fire-arms. To supply this desideratum is the object of my invention.

The drawings represent a quantity of detonating material, *a*, cased with two metallic cylindrical shallow boxes, that fit into each other like the bottom and lid of a common apothecary's pill-box. One part, *b*, is of less diameter than the other part, *c*, and the open end of the lid *b* is inserted within the bottom *c*. The two thus united present two flat faces or ends joined by a side edge or periphery of two thicknesses, as represented in Fig. 4. Before, however, thus fitting these two half-boxes together the detonating material is inserted in the smaller part *b*, so that it may be inclosed securely when the half-boxes are fitted together, as described. The boxes thus united and containing the percussion material are placed within a die or chamber of the size of the outer

box, and pressure is brought to bear upon their faces or ends, which action has the effect of forming an annular crimp round their peripheries, as represented in Fig. 5, so that the two boxes are permanently united, and, when removed from the die, cannot easily be separated. By varnishing the pellet thus formed with a solution of gum-shellac in alcohol, so as to fill the joints, the detonating powder will be hermetically sealed, so that it will be perfectly preserved. Such a close pellet is especially adapted to self-priming fire-arms, and in the drawings it is shown as intended to be used in connection with a lock similar to that described in my specification for an improved method of priming fire-arms, for which Letters Patent were granted to me bearing date the 5th day of October, in the year 1852.

The magazine *A* of the musket is a tubular chamber formed by an enlargement of the lock-plate. This chamber *A* is of somewhat larger diameter than the pellet to be used, and is of equal bore throughout except at the top, where it is conical, being slightly contracted, so as to leave an opening of about the size of the pellet.

A cap, *C*, is screwed into the lower end of the chamber, and a piston, *D*, fitted within the chamber. The piston *D* is of conical form on its upper face, corresponding with the conical mouth of the chamber, which the piston, when raised, shuts in the manner of a valve.

A flat helical spring, *E*, is inserted beneath the piston, which constantly tends to raise it. The thinness of the spring, together with a cavity in the cap *C* to receive the stem of the piston, prevents the piston and spring from occupying much space in the chamber when the spring is compressed, and consequently leaves a large chamber for the storing of pellets, while the conical shape of the piston *D* and mouth of the chamber *A* prevents the piston from being forced out of the magazine by the spring, and as the piston rises to the same level as the upper face of the magazine the piston expels every pellet in succession from the magazine, causing them to be received under the projecting end *x* of a sliding cap, *F*. The space beneath the end *x* of the cap *F* is of such depth that when situated over the chamber *A* it will receive but one pellet at a time by the pressure upward of the piston *D*.

The pellets *a* are stored one upon the other on the piston *D*, as represented in Fig. 1, and are delivered one by one, as required, from the mouth of the chamber *A* by drawing back the slide *F*—that is, one for each discharge of the musket. The sliding cap *F* is thus drawn back for receiving a pellet by raising the cock, is shot forward by the descent of the cock to discharge and deliver the pellet at the place for its explosion, when the further action of the cock adjusts the sliding cap *F* to receive the next pellet, which the piston *D*, by its pressure upward, supplies until the pile of pellets in the magazine *A* are exhausted.

In order that the magazine *A* may be filled with dispatch, and the pellets prevented from entering edgewise, I employ a charger, *G*, which consists of a slotted tube, *e*, of such diameter at the top as will freely admit the pellets, but contracted at the bottom to a diameter somewhat less than that of the pellets, so that they are prevented from dropping out of the tube *e*, which is rendered elastic by slightly reducing the thickness of the metal and cutting slots or openings *s* at regular distances apart round the bottom or lower end of the said tube *e*.

A piston or follower, *f*, is fitted within the tube *e*, and projects through the longitudinal slot *x* thereof.

To fill the charger *G* the follower *f* is withdrawn from the tube by sliding it out through the upper end of the tube. The flat pellets, already described, are then introduced flatwise at the larger or upper end of the tube *e* in a sufficient number to nearly fill the tube. The follower *f* is then inserted within the tube, and the charger is ready for use.

To load or replenish the magazine *A*, the contracted and spring end of the tube *e* is inserted in the mouth of the magazine, the follower *f* is then pressed forcibly downward, so as to project the pellets through the lower end of the tube, that yields sufficiently to allow them to pass into the magazine, the continued action

of the follower by pressure thereon forcibly pressing down the piston *D* till the charger is emptied and the magazine filled, when, without removing the follower, the charger is moved aside from the mouth of the magazine by pushing the cap *F* against the lower end of the tube *e*, the cap preventing the piston *D* from forcing the pellets out of the magazine at once, as it would do if the cap were not placed over its mouth.

Any less number than a full charge of pellets may be transferred from the charger into the magazine, as occasion requires, by only partially depressing the follower, and the loaded charger may be kept with perfect safety in the pocket of the gunner for replenishing the magazine, as required.

This charger affords much facility and expedition in the loading of the magazine, insures the entrance of the flat pellets therein in proper order, and is a safe, simple, and convenient contrivance for carrying the pellets. It also is of so light, cheap, and portable a character that a large number of them containing full magazine-charges may be put up in packages ready for immediate use as an article of merchandise.

What I claim as my invention, and desire to secure by Letters Patent, is—

The percussion-pellet herein described, consisting of a quantity of detonating material enclosed between two flanged disks or shallow hollow cylinders, closed at one end, the open end of one cylinder being fitted into the open end of the other, and the two being firmly interlocked by crimping together their flanges, rims, or peripheries, substantially as described, so as to form a pellet in the form of a disk.

In testimony whereof I have hereunto subscribed my name.

CHRISTIAN SHARPS.
